UNITED STATES PATENT OFFICE.

ANTON WOLZ, OF ST. LUZI, CHUR, SWITZERLAND.

INKSTAND.

No. 878,922.

Specification of Letters Patent.

Patented Feb. 11, 1908.

Application filed September 12, 1906. Serial No. 334,250.1

To all whom it may concern:

Be it known that I, ANTON WOLZ, a citizen of the Confederation of Switzerland, residing in St. Luzi, Chur, in said Confederation, have 5 invented certain new and useful Improvements in Inkstands, of which the following is a specification.

This invention relates to inkstands, and more particularly to stationary inkstands 10 such as are fitted in the top of a desk or table.

The object of the invention is to provide an inkstand of this type wherein the ink in the well into which the pen is dipped can be 15 kept always at the same level in a very simple manner, this level being regulated in order to supply exactly the proper amount of ink to the pen. With this end in view the invention consists in an inkstand embodying 20 the novel features of construction to be hereinafter described and claimed.

In the accompanying drawing, in which the same reference characters denote the same parts throughout the several figures, 25 Figure 1 is a vertical section of an inkstand constructed in accordance with the invention, the same being shown as mounted in a mortise or socket of a desk or table, Fig. 2 is a plan view of Fig. 1, but with the cover re- 30 moved, and Fig. 3 is a plan view of the body of the inkstand with the ink-well fitting therein.

In the drawing *a* denotes a socket or mortise in the top of a desk or table. Said mortise is preferably made square in horizontal section, as indicated by the dotted lines in Fig. 2, and the desk is provided with a circular rabbet *a*^x extending about said socket at its upper part. Movable vertically in the 40 socket *a* is an ink-receiving body *a*¹, which is of cylindrical shape throughout the greater part of its height, but provided with a substantially square base *b*¹ fitting rather snugly in the socket *a* and by means of which said body 45 is guided vertically in the socket. Said body is provided at its upper part with a conical ink-receiving cavity and is threaded exteriorly so as to be engaged by a threaded adjusting sleeve *d* which fits within the socket 50 of the desk and is provided at its upper end with a laterally extending flange *d*² resting in the rabbet *a*^x. By means of said flange the adjusting sleeve and the ink-receiving body in threaded engagement therewith are sup-

ported within the socket. Upon the upper 55 surface of the flange *d*² are upwardly extending lugs *d*³ by which the flange may be grasped in order to turn the adjusting sleeve *d* in either direction.

An ink-well *e*, of substantially conical form, 60 fits within the cavity of the body *a*¹. At its lower part said well is provided with a small opening *e*² through which the ink flows into the body *a*¹. At its upper edge the well *e* is provided with a laterally extending flange 65 *e*¹ which rests on the upper edge of the flange *d*² of the adjusting sleeve *d* in such a manner that the well is supported on said sleeve. A cover *f* having a knob *f*¹ fits over the well *e* and is provided with an interior flange *f*² extending downwardly into the well for a short 70 distance in order to form a tight connection between the cover and well.

In operation the inkstand is filled when the body *a*¹ has been screwed down into the bottom of the socket by means of the adjusting sleeve *d*. The ink is then poured into the well *e* through which it runs, by means of the opening *e*², into said body. A line *x* is preferably marked on the inner surface of the 80 well to indicate the height to which the ink should extend. As the ink becomes gradually exhausted, it will become necessary to raise the body *a*¹ in order to bring more ink up into the well, and this is effected by 85 screwing the adjusting sleeve *d* in the proper direction; said sleeve, though rotating, will remain immovable vertically, together with the well *e*, but the body *a*¹, being unable to rotate in the socket, will be raised or lowered 90 according to the direction in which the sleeve is turned, being guided in its movement by the square base *b*¹.

It is apparent that the adjustment of the body can be very readily effected by turning 95 the adjusting sleeve as described. In this simple manner the ink can always be kept at the same level in the ink-well and supplied in proper quantity to the pen. By raising the ink-receiving body as far as possible all the 100 ink can be used up, so that no waste will be occasioned. It is apparent that the whole device may be lifted out of the socket in the desk when desired.

Having thus described my invention, I 105 claim as new and desire to secure by Letters Patent:

1. The combination, with a part having a

socket, of an ink-receiving body movable vertically therein, a rotary adjusting sleeve supported in said socket, and a well supported on said sleeve and extending downwardly 5 into said body.

2. The combination, with a desk having a mortise or socket, of a threaded ink-receiving body guided vertically in said socket, a threaded adjusting sleeve having a flange at 10 its upper end by which it is supported in said socket, and an ink-well fitting within said ink-receiving body and supported by said sleeve.

3. The combination, with a part having a 15 socket, of a threaded ink-receiving body in said socket, means whereby said body is guided vertically in said socket and prevented from rotation therein, an adjusting sleeve rotatable in said socket and threaded on said 20 body, and means supported on said sleeve to contain a supply of ink.

4. The combination, with a desk having a socket of square cross-section, of an exteriorly threaded ink-receiving body having a 25 square base fitting within said socket, an adjusting sleeve embracing said body and threaded thereon and mounted to rotate in

said socket, and an ink-well supported by said sleeve.

5. The combination, with a desk having a 30 socket and a rabbet about the upper edge of said socket, of an ink-receiving body guided vertically in said socket, an adjusting sleeve threaded on said body and having a flange resting in said rabbet, and an ink-well supported by said adjusting sleeve and fitting within said ink-receiving body. 35

6. The combination, with a desk having a 40 socket, of an ink-receiving body guided vertically in said socket, an adjusting sleeve by 45 which said body is raised and lowered having at its upper end a supporting flange, upwardly extending lugs on said flange by which the sleeve is manually turned, and an ink-well having a flange supported on said sleeve at the upper end of the latter.

In testimony that I claim the foregoing as my invention I have signed my name in presence of two subscribing witnesses.

ANTON WOLZ.
